UNITED STATES PATENT OFFICE.

GEORGE F. VOIGHT, OF SAN FRANCISCO, CALIFORNIA.

LUBRICATING DEVICE FOR SPRINGS.

1,084,181.

Specification of Letters Patent. Patented Jan. 13, 1914.

Application filed August 18, 1913. Serial No. 785,385.

To all whom it may concern:

Be it known that I, GEORGE F. VOIGHT, a citizen of the United States, residing at San Francisco, in the county of San Francisco and State of California, have invented a new and useful Lubricating Device for Springs, of which the following is a specification.

The present invention relates to improvements in lubricating devices for leaf springs, one object of the invention, being the provision of means whereby the leaves of the springs where the same contact, are forced apart and lubricant is injected therebetween, the lubricant thus preventing the rusting between the springs and at the same time reducing the friction between the leaves when the tension is placed upon them and relieved.

A further object of the present invention, is the provision of a novel means, whereby the leaves of the springs are first separated and a proper spacing is produced to permit of the introduction of the lubricant therebetween, there being provided for this purpose, two prying members, for introduction between the leaves at opposite points, one of the wedging members being connected to a lubricating device by means of which the lubricant is injected through the wedging member between the leaves.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a side elevation, partly in section of the preferred form of the present device. Fig. 2 is a top plan view thereof with a portion of the leaf spring broken away to show the parts in the proper position. Fig. 3 is a view in elevation and partly in section of a modified form of the present invention. Figs. 4, 5 and 6 are detail views of parts of the devices shown in Fig. 3. Fig. 7 is a view similar to Fig. 3 of another modified form of lubricating device. Figs. 8, 9 and 10 are detail views of various parts of the device shown in Fig. 7. Fig. 11 is a view similar to Fig. 3 of another modified form of the present invention. Fig.

12 is a section taken on line 12—12 of Fig. 11. Fig. 13 is a section taken on line 13—13 of Fig. 11. Fig. 14 is a detail view of the device as shown in Fig. 11. Fig. 15 is a detail view of still another modified form of the present invention. Figs. 16, 17 and 18 are detail views of the device as shown in Fig. 15.

Referring to the drawings, and more particularly to Figs. 1 and 2 thereof, the numeral 1 designates a yoke frame which, as shown, is provided with the terminal 2 threaded at 3 to receive the feed screw 4. This feed screw 4 is provided with the pointed prying end 5 and with the manipulating winged member 6. The terminal 8 is disposed in parallel with the terminal 2 and, as shown, is provided with the fixed or integral prying member 9 which, as shown, is tapered toward its prying end and is provided with the centrally disposed recess or notch 10. Formed through the body of the prying member 9 and in communication with the notch 10, is a duct or channel 11, which leads to the threaded portion 12, which receives the reduced end 13 of the lubricant cup 14. The member 15 of the lubricating device is disposed as in the usual form of grease cups, so that the same may be operated to cause the forcible ejection of the lubricant through the duct 11 and the notch 10 of the prying device 9 into the space 7 between the respective leaves of the spring S. It will thus be seen that with the present device, the terminals 2 and 8 may be disposed at each side of a leaf spring, so that the prying member 9 will be disposed first at one side of the spring and that when the feed screw 4 is rotated to cause the cylindrical prying member 15 to be interposed between the same members of the spring, the respective leaves of the spring will be spaced apart to produce the space 7, as shown in Fig. 1, so that when the lubricating cup 15 is rotated to cause the lubricant therewithin to be forced through the port 11, the recess or notched end 10 will permit of the proper introduction of the lubricant into the space 7, so that when the prying members are released from the leaf springs, the lubricant will be properly disposed upon the adjacent faces of the leaves of the springs. By this means it will be seen that lubricant may be quickly and easily introduced between the leaves and that thus the

friction at such points will be greatly reduced and consequently the life of the spring be increased.

In Figs. 3, 4, 5 and 6, a slight modification of the present device is shown, the yoke 1' being provided with a fixed prying point 9', while the feed screw 4', carrying the grease or lubricant supplying cup 15 and the manipulating handle 17, has disposed upon its inner end, through the means of the pin and slot $a-a'$, the lubricant introducing prying member 16. This member is flat as is the member 9 and is provided with the lubricant ejection notch 10' corresponding with the notch 10 of the member 9 and it has the port 11' which is in communication with the port 18 of the feed screw 4'. Thus the present device may be positioned similarly to the device shown in Figs. 1 and 2, with the prying and lubricant supplying member 16 properly positioned between the leaves of the springs, the screw 4' being rotated through the medium of the disk handle 17, and the proper necessary movement imparted to the member 16 through the connection at $a-a'$ between it and the screw 4'.

In the form of device shown in Figs. 7, 8, 9 and 10, a projection 19 is carried by the yoke and is socketed to receive the lubricant supplying and prying member 16', which is made somewhat similar to the member 16 and is provided with the lubricant directing notch 10' in its forward reduced edge. The screw 4' which corresponds to the screw 4 is mounted in the member 19 and carries upon its ends, the lubricant cup 14' which forms a handle for rotating the screw 4', the plunger 15' for the lubricant being disposed within the cup so that the lubricant is properly ejected through the prying lubricating member 16' which is disposed to align with the fixed prying member 9' of the device. A groove and pin connection $b-b'$ connects the prying head 16' with the screw 4' and thus provides a means whereby the screw 4' may be rotated without rotating the member 16'. The groove b and the two parallel pins b' , as illustrated in Fig. 10 are employed to hold the prying member 16' to the screw 4', so that the screw 4' may be rotated without imparting rotation to the member 16'.

In the form of device shown in Figs. 11, 12 13 and 14, a cylindrical bar or rod 20 is employed and has attached to one end, the upstanding arm 21 provided with the stationary spring prying wedge member 22 and the opposite end with the arm 23, provided for the reception of the feed screw 4'. Disposed upon the rod 20 between the arms 21 and 23 for sliding movement is the arm 24, which carries at its opposite upper end, the lubricant supplying and prying member 24' which is provided with the notch 10' similar to the notch 10 of the device shown in Fig.

1. The screw 4' is connected through the joint 25 to the arm 24, so that the rotation of such screw will impart the necessary sliding movement to the lubricating and prying member 24', the arm 21 with its connection to the rod 20 insuring the proper alining of the same with the prying member 22. The lubricant supplying member 14' which constitutes a handle for the screw 4' is disposed upon the outer end thereof and is provided with the plunger 15'. 70 75

In the devices as shown in Figs. 15, 16, 17 and 18, a cylindrical stem 26 is provided and carries at one end the upstanding arm 27 provided with the fixed prying member 28, the opposite end 29 being threaded for the reception of the operating wing nut 30. Disposed for sliding movement upon the stem 26 is a sleeve 31, which carries the arm 32. This arm 32 is provided with the enlarged upper end 32' and with the forward recessed rib or projection 33 formed integral therewith. A port 34 is provided in the end 32' and leads into the threaded socket 35 for the reception of the threaded connection 36 of the lubricant supplying device 37. The lubricant supplying and prying point or member 38, in the present instance, is composed of a different material, preferably a harder or more highly tempered metal than the arm 32, and is attached to the lug 33 through means of the rivets or screws 39. A channel or port 40 is provided in the member 38 and the same is disposed to align with the channel 34, so that lubricant may be supplied from the member 37 through the notch 10', which is formed in the reduced prying end of the member 38 similar to the notches heretofore described in the other members. 80 85 90 95 100 105

From the foregoing description, taken in connection with the drawings it is evident that all forms of the present device embody oppositely disposed means for prying or separating the various leaves of the spring, one of such prying points being provided with means whereby lubricant is supplied at the proper point between the leaves. 110

All forms of the prying and lubricant supplying members are provided with a single notch whereby the lubricant is properly introduced at the desired point of application. All forms are also provided with means whereby the proper pressure is exerted to pry the leaves of the springs apart before the final introduction of the lubricant therebetween. 115 120 125

What is claimed is:

1. A leaf spring separator and lubricator, including two oppositely disposed spring engaging and prying members, means for moving one member to and from the other member, one of said prying members at its free end being provided with a lubricant introducing notch, and a lubricant supplying 130

device in communication with the notched prying member.

2. A leaf spring separator and lubricator, including a frame, two upstanding arms carried by the frame, two oppositely disposed spring engaging and prying members carried by the arms, means for moving one of the prying members to and from the other member, and means for introducing lubricant adjacent the prying point of one of the members.

3. A leaf spring separator and lubricator, including a frame, two upstanding arms carried by the frame, two oppositely disposed spring engaging and prying members carried by the arms, means for moving one of the prying members to and from the other member, one of the prying members being provided with a lubricant introduction notch in the end thereof, and a lubricant supplying means connected to the prying member for supplying lubricant through the notch.

4. A leaf spring separator and lubricator, including two oppositely disposed spring en-

gaging and prying members, said members being disposed for movement to and from each other and in axial alinement, one of the prying members being provided with a notch in the free end thereof, and means 30 connected with the latter prying member for introducing a lubricant through the notch thereof.

5. A leaf spring separator and lubricator, including two oppositely disposed spring 35 engaging and prying members, said members being disposed for movement to and from each other and in axial alinement, one of the prying members being provided with a chisel-like point having a central notch in 40 the pointed edge thereof, and a lubricant supplying member carried by the chisel-shaped prying member.

In testimony that I claim the foregoing as my own, I have hereto affixed my signature in the presence of two witnesses.

GEORGE F. VOIGHT.
